A. F. KRUSCHKE.

SIGN BOARD.

APPLICATION FILED SEPT. 24, 1919.

1,358,000.

Patented Nov. 9, 1920.

UNITED STATES PATENT OFFICE.

ALEXANDER F. KRUSCHKE, OF MELVIN, ILLINOIS.

SIGN-BOARD.

1,358,000.

Specification of Letters Patent.

Patented Nov. 9, 1920.

Application filed September 24, 1919. Serial No. 325,877.

To all whom it may concern:

Be it known that I, ALEXANDER F. KRUSCHKE, a citizen of the United States, residing at Melvin, in the county of Ford, 5 State of Illinois, have invented certain new and useful Improvements in Sign-Boards; and I do hereby declare the following to be a full, clear, and exact description of the invention, such as will enable others skilled 10 in the art to which it appertains to make and use the same.

This invention relates to new and useful improvements in signs and particularly to sign boards.

15 One object of the present invention is to provide a novel and improved form of sign board whereon notices of various sizes and characters may be applied and others subsequently applied without presenting an un- 20 slightly appearance.

Another object is to provide a novel and improved sign board which is equipped with novel and improved means for holding notices.

25 Other objects and advantages will be apparent from the following description when taken in connection with the accompanying drawing.

In the drawing:

30 Figure 1 is a front elevation of a sign board made in accordance with my invention.

Fig. 2 is an enlarged vertical sectional view taken on the line 2—2 of Fig. 1, 35 through one of the holding frames to show the spring hinges and latch for the frame.

Referring particularly to the accompanying drawing, 10 represents a pair of uprights each of which is provided with the 40 transversely extending feet portions 11 whereby said uprights will be maintained in vertical position. Between these uprights there is disposed a large board 12, the opposite vertical edges of which are 45 provided with trunnions 13 for engagement in the bearings 14 in the uprights for permitting pivotal movement of the board on the uprights. Carried by the inner verti-

cal edge face of each of the uprights is an inwardly extending lug or pin 15 which is 50 arranged to engage with the rack arm 16 which is pivotally carried by the vertical edge face of the board. By means of these rack arms and the said lugs or pins, the board can be tilted to assume any desired 55 angle and there held.

Secured on the front face of the board are a number of rectangular or otherwise shaped frames 17, said frames being attached to the board at their lower edges by 60 means of the spring hinges 18. Carried by the face of the board above each of the frames is a spring latch 19 adapted to engage over the upper portion of the frame to hold the same firmly against the face of 65 the board and to properly and smoothly hold a sheet of paper, having the desired printing thereon, in a flat condition against the face of the board.

By this construction the old notice or 70 sign can be readily and quickly removed and the new one put in its place. Also, if desired, the old notice can be retained by the frame, in a position directly behind the new sign. 75

What is claimed is:

In a sign board, the combination with a pair of uprights having feet at their lower ends and bearings at their upper ends, and rack bars pivoted to said uprights below 80 their bearings; of a board between the uprights and having trunnions journaled in said bearings, pins on the board for engagement with said rack bars to hold the board at the desired position, frames hinged 85 at their lower ends to the face of the board, and spring latches for holding their upper ends against such face, for the purpose desired.

In testimony whereof I affx my signature 90 in the presence of two witnesses.

ALEXANDER F. KRUSCHKE.

Witnesses:

PAUL KRUSCHKE,
HARRY KRUSCHKE.
